UNITED STATES PATENT OFFICE

163,494

WATCH BAND OR SIMILAR ARTICLE

Gustave G. Toth, Woodland Hills, Calif., assignor
to Gershgorn & Co., Inc., Los Angeles, Calif.,
a corporation of California

Application May 26, 1950, Serial No. 10,217

Term of patent 3½ years

(Cl. D45—4)

To all whom it may concern:

Be it known that I, Gustave G. Toth, a citizen of the United States, residing in Woodland Hills, county of Los Angeles, State of California, have invented a new, original, and ornamental Design for a Watch Band or Similar Article, of which the following is a specification, reference being had to the accompanying drawing, forming part thereof.

Figure 1 is a plan view of a watch band showing my new design;

Figure 2 is an edge view thereof;

Figure 3 is a side view thereof.

I claim:

The ornamental design for a watch band or similar article, substantially as shown.

GUSTAVE G. TOTH.
